TWIN ROLL TOILET TISSUE HOLDER

Lydia J. Scott, Castro Valley, Calif.

Filed Oct. 16, 1961, Ser. No. 67,099

Term of patent 7 years

(Cl. D4—3)

Fig. 1

Fig. 2

The side not shown is substantially like the side shown.

I claim:

The ornamental design for a twin roll toilet tissue holder, substantially as shown.
